(57) **CLAIM**

The ornamental design for a display screen with graphical user interface, as shown and described.

DESCRIPTION

FIG. 1 is a front view of a display screen with graphical user interface showing our new design; and,

FIG. 2 is a front view of the display screen with graphical user interface shown on a device thereof.

The broken lines showing the remainder of the graphical user interface, the remainder of the display screen, and the device are for environmental purposes only and form no part of the claimed design.
